Hoboken, N. J., a corporation of New Jersey

Application January 28, 1936, Serial No. 61,131

13 Claims. (Cl. 242—25)

This invention relates to spooling or reeling mechanism of wire drawing apparatus or the like and provides improvements therein.

The general construction and operating characteristics of wire drawing and spooling machines may be summarized as follows: The machine comprises a plurality of dies of progressively smaller size and a capstan after each die, the capstans being so driven as to have progressively higher peripheral speeds occasioned by the elongation of the wire in passing through each die. For the purpose of avoiding breakage of the wire, the machines are so designed that the peripheral speed of each capstan-drum is somewhat less than the peripheral speed of the preceding capstan-drum plus the elongation of the wire in passing through the preceding die, so that there is a continual "slip" of the wire on the capstan-drums through the machine. That is, while the wire is pulled forward all the time, its speed is less than the peripheral speed of the capstan-drums by the amount of slip which occurs. The amount of slip is governed by the difference between the actual, or designed, peripheral speed of each capstan-barrel, and the required peripheral-speed to correspond to the speed of the wire on leaving the preceding capstan-barrel plus the elongation in passing through the preceding die, and also by the pull on the wire after it leaves the last capstan-barrel.

The capstans are driven at a constant speed, and the requisite of proper operation is that the wire should be pulled from the final capstan by the spooling mechanism at a speed approximately but not fully equaling the peripheral speed of the final capstan, to thereby admit of the "slip" within the wire drawing machine hereinbefore referred to. It is desirable, and even necessary in high speed machines, to prevent "burning" of the wire, to limit the maximum of the "slip", and therefore to maintain at all times a peripheral speed of the wire on the spool (notwithstanding the increase in diameter of the coil as successive layers are wound on the spool) which always approximates the peripheral speed of the final capstan, so that the amount of variation of the winding or spooling speed from the peripheral speed of the final capstan shall never be too large. For the purpose just referred to, the device most generally used has been a fabric or leather belt running around a pair of pulleys, one flight of which makes contact with the coil of wire on the spool, and rotates the spool through such contact. Such a belt-device has a number of objections, some of which are,

variability of driving force imparted by the belt to the spool, disintegration of the belt upon the coil, the rapidity of the wear and disintegration of the belt, and the susceptibility of the belt to the collection of dirt.

It has also been proposed to employ an arm having a roller thereon which runs against the bobbin or coil of wire on the reel or spool, which is displaced as the layers of wire build on the reel or spool and by such displacement operate a speed-changing device to progressively diminish the speed of rotation of the reel or spool spindle. With high speed wire drawing machines (6000 to 10,000 feet per minute for example) the velocity factor makes the action of masses which in slower running machines are inconsequential, severe and detrimental. The wire is damaged and a throbbing-effect is produced in the speed-changing device and in the spindle driving mechanism.

Moreover, to prevent "burning" of the wire, there is less latitude in the degree of "slip" in high speed machines than in the older and slower machines.

The present invention provides a novel and improved spooling or reeling mechanism and one which is especially adapted for use as a part of or conjointly with a wire drawing machine. It provides a mechanism of the character referred to in which a diminishment of speed of rotation of the spool or reel is closely responsive to increase of diameter of the wire-coil during spooling and relatively steady; which is suited to and adequate for satisfactory operation at high wire drawing speeds; which operates satisfactorily with unsymmetrical spools or coils; which does not detrimentally affect the wire winding on the spool or reel; which admits of ready removal and replacement of spools; and which is durable, of relative simplicity, and reliable in operation.

Furthermore, the present invention provides an apparatus no part of which makes contact with the wire winding on the spool or reel more than momentarily, which is not responsive to irregularities in the cylindrical contour of the bobbin or coil of wire, which only contacts with the high spots on the bobbin or coil from which it results that the impact between the wire in the coil (high spots thereof) and the part of the speed-changing means which contacts with wire, is light, and fluctuations or throbbing of the spindle driving mechanism avoided.

The present invention further provides an apparatus wherein the work of shifting the change-speed device and also of the part which makes

contact with the wire winding on the spool or reel, is done otherwise than by force derived from the rotating reel or spool and the wire winding thereon. By the present invention an independent motor or actuating means is provided for shifting the variable speed device and the part which contacts with the bobbin or coil on the spool or reel, and the said part which contacts with the bobbin or coil only performs the work of initiating the action of said independent motor or actuating means, and consequently can be made extremely light. By the present invention, the action of the spindle-driving mechanism which includes the change-speed device is made positive and regular, and the range of speed-change widened.

Several embodiments of the invention are illustrated in the accompanying drawings, wherein

20 Fig. 1 is a view in side elevation of a wire drawing machine comprising a reeling or spooling mechanism;

25 Fig. 2 is a view in side elevation, on an enlarged scale, of the spooling or reeling mechanism shown in Fig. 1.

Fig. 3 is a vertical sectional view on the line 3—3, Fig. 2.

30 Figs. 4 and 5 are detailed views of parts of the spooling mechanisms shown in Figs. 1, 2 and 3, in side and front elevation respectively, illustrating the part for measuring the radius of the coil winding on the spool;

35 Figs. 6 and 7 are respectively detailed views in side and front elevation, of parts of the spooling mechanism and illustrating a second embodiment of the means for measuring the radius of the coil on the spool and independent actuating or motor means for doing the work of changing the speed of the spindle on which the spool is mounted is 40 driven, and of shifting the parts in contact with the coil on the reel or spool.

Fig. 8 is a diagram of an electrical arrangement such as may be used in the embodiment illustrated in Figs. 6 and 7. This electrical arrangement may also be used in the embodiment illustrated in Figs. 10 and 11.

Fig. 9 is a detailed view illustrating the modification of the pawl 64 shown in Figs. 1 to 5 inclusive.

50 Fig. 10 is a view in side elevation of a third embodiment of the spooling or reeling mechanism providing independent motor means for actuating the speed-changing device, etc.; and

55 Fig. 11 is a section of the mechanism shown in Fig. 10 on the line 11—11.

Referring to said drawings, numeral 10 designates the wire drawing part of the machine, and 12 the spooling or reeling mechanism. The wire drawing part of the machine comprises a series 60 of wire drawing dies 13, and capstans 14, 15, and has the operating characteristics hereinbefore described.

65 The spooling or reeling mechanism 12 comprises a spindle or other suitable means 18 for supporting and rotating a reel or spool S, the spindle being driven to rotate the spool. When the spooling mechanism forms a part of a wire drawing machine, the spindle is preferably driven from a part of the wire drawing mechanism, as by 70 the shaft 20 which drives the final capstan 15. If the spool spindle 18 were rotated at constant speed, its speed of rotation would have to be such that the peripheral speed of the coil of wire at its greatest diameter during winding on the spool S 75 would not exceed the peripheral speed of the final

capstan 15. With such an arrangement there would be a large amount of slip in the wire drawing mechanism during the initial stages of the spooling of the wire, which is undesirable, and which, in high speed wire drawing machines, 5 would be excessive, causing damage to the wire, such as friction "burning", etc. It is therefore desirable to drive the spool spindle 18 in such manner that the peripheral speed of the coil of wire on the spool S, as the layers of wire build 10 thereon during winding, shall closely approximate the peripheral speed of the final capstan 15 throughout the drawing and spooling operation. Such operation is particularly important in wire drawing machines in which the wire is drawn 15 at high speeds.

To such end, a means 25 is provided for changing the speed of or in the mechanism for driving the spool spindle 18 in accordance with the change in radius of the coil of wire on the spool 20 by reason of the change in the layers of wire in the coil. In reference to a wire drawing mechanism the aforesaid means would act to progressively diminish the speed of rotation of the spindle 18 as the radius of the coil of wire builds with 25 successive layers winding on the spool. The means for changing the speed of the driving mechanism in accordance with the change in radius of the coil comprises any suitable means by which the speed of rotation of the shaft 18 30 may be changed, (one form of which is a variable transmission in the driving means, shown herein on the drawing at 30) and a means for acting on or controlling said speed changing means in accordance with the change in radius of a coil of 35 wire on the spool or reel S by reason of a change in the layers of wire on the coil. The latter means may have various forms of embodiment, three of such forms being illustrated at 31, 31a, and 31b in the drawings.

The means for driving the spool spindle 18 in the form here illustrated comprises a drive shaft (here shown as the capstan shaft 20 driven in suitable manner as by means of a sprocket wheel 35, Fig. 3, or a pulley 35a, Fig. 11), and a variable 45 transmission which may be of the type herein illustrated. As shown, the variable transmission comprises a fixed diameter pulley 33, a pulley 37 of variable diameter, and a belt 39 passing around the pulleys 33 and 37. The pulley 37 comprises 50 two discs 41, 42 having oppositely inclined faces forming a V-shaped surface with which the belt 39 makes contact. One of the discs, as the disc 41, is fixed upon a shaft (which may be, as here 55 shown, the spindle shaft 18), and the other of which, as the disc 42, is adjustable longitudinally of the shaft to vary the width of the V between the faces of the two discs 41, 42. The disc 42 is rotatably connected to a sleeve 44 surrounding the shaft 18, which sleeve 44 has a 60 thread thereon which engages a threaded part 45 on a fixed part of the machine, the arrangement being such that when the sleeve 44 is rotated the thread engagement between the sleeve 44 and the part 45 produces a movement of the sleeve 44 65 longitudinally of the shaft 18, and a similar movement of the disc 42 of pulley 37. An arm and a roller 48 serves to maintain the belt 39 under tension throughout adjustment of the variable diameter pulley 37.

70 The means for acting on the speed changing means may, as heretofore stated, have a variety of forms. One form is shown at 31, Figs. 1, 2, 3, 4 and 5. It comprises a means 50 for measuring the change in radius of the coil of wire on the 75

spool by reason of the change in the layers of wire in the coil, and means for transmitting or translating such measurements to the speed changing means. In said embodiment the radius 5 measurer 50 is in the form of an arm pivoted or mounted on a shaft or axis 52, and the arm is arranged to swing toward and from the axis of the spool of spindle 18, and to contact with the coil of wire as it winds on the said spool S. In 10 said embodiment the displacement of the arm or part 50 is arranged to act directly upon the variable transmission 30 or other speed changing means. As shown the arm 50 is fixed on the shaft 52 and the shaft 52 has a toothed sector 54 which 15 engages a toothed gear 55 on the sleeve 44, which sleeve 44, as heretofore described, moves longitudinally of the shaft 18 and thereby adjusts the disc 42 of the variable diameter pulley 37. The displacement of the part 50 however can be transmitted to the variable speed pulley 37 by various 20 other mechanical arrangements.

Means are provided for stopping the return movement of the radius measuring part 50 toward the axis of the spindle 18, which means, in 25 the embodiment shown in Figs. 1 and 5, has the form of an arm 60 mounted on a sleeve 62 with the arm 50 in such manner that the arms 50 and 60 move together. The arm 60 has thereon a pawl 64 engaging a rack segment 66 having teeth 30 pointing in a direction to prevent movement of the arms 50 and 60 toward the axis of the spool spindle 18. In order to minimize the return movement of the arm 50, the pawl 64 may be made in several parts 64^a, 64^b, 64^c of different 35 length, as illustrated in Fig. 9. By such a construction the return movement of the arm 50 may be limited to a fraction of the length of a tooth on the rack segment 66.

Such a construction has the advantage of 40 avoiding fluctuations in the drive of the spool due to unsymmetry of the coil on the spool, and also of avoiding heavy impacts between the arm 50 and the wire winding on the spool. This unsymmetry may rise from several causes. For 45 example, the spool may be unsymmetrical, and usually is to some extent. Such a condition of unsymmetry is indicated by the dotted line x in Figs. 4, 6 and 8.

Instead of the work of shifting the variable 50 transmission 30 or other speed changing means being done directly by the radius measuring part 50, it may be done by an independent actuating or motor-device of any suitable kind the radius-measuring part 50 acting to initiate the action of 55 the motor device. Furthermore the work of displacing the part 50 may also be done by the said independent actuating or motor-device.

An embodiment in which the work of shifting the variable transmission 30 or other speed 60 changing means and of displacing the measuring part 50 is done by an independent motor, is illustrated in Figs. 6, 7 and 8, and another such embodiment in Figs. 10 and 11. Referring to Figs. 6, 7 and 8, 160 designates a motor-device in the 65 form of a solenoid and armature. Movements of the armature may be transmitted to the sleeve 44 of the variable transmission 30 by a pawl 162 (Fig. 6) engaging a ratchet wheel 166 fixed on the shaft 52 having thereon the gear segment 54 shown in Fig. 3. The pawl 162 is mounted on a shaft 162^a having an arm 67 connected to the armature of the motor-device 166, and having a screw-thread engagement with its support, as indicated at 68. When the armature is pulled toward 70 the solenoid, the shaft 162^a is turned and

advances the pawl 162 to turn the ratchet wheel 166 stepwise, a holding pawl 70 acting to hold the ratchet wheel against back-movement when the pawl 162 is retracted. The solenoid 166 may be electrically energized consequent upon contact of the measuring part 50 or a finger 75 thereon with the coil of wire on spool S. As shown the finger 75 is pivotally mounted on the arm and carries thereon one terminal of a make and break device 78. The finger 75 may be made extremely light. 10 Contact of finger 75 with the coil of wire on spool S breaks a circuit at 78 momentarily and brings about a flow of current to solenoid 166, in the following manner. A wiring diagram of a suitable circuit arrangement is shown in Fig. 8. 15

A circuit from the low-tension side of a transformer 80 through a relay 82, is broken when the make and break device 78 is opened. Thereupon relay 82 closes a circuit through contacts 84 and through a relay 86, which latter is energized to 20 close contacts 88, 89. The closing of contacts 89 establishes a holding circuit through the relay 86, and the closing of contacts 88 establishes a circuit through the solenoid of motor 166, and causes its armature to turn the shaft 162^a through 25 arm 67 and thrust pawl 162 forward to turn the ratchet-wheel 166 through an angular distance of one tooth, thereby moving the arm 50 away from the axis of spool-spindle 18, and acting on the speed changing means through shaft 52. The 30 movement of arm 50 also allows finger 75 to retract to close contacts 78, reenergize relay 82 and cause it to break the circuit at contacts 84. The action of the armature of motor 166 on arm 67 also operates to break the circuit through the 35 solenoid of motor 166 at a make and break device 90, and thereby reset the armature, shaft 162^a and pawl 162 for another operation.

In the embodiment illustrated in Figs. 10 and 11 the work of retracting of the measuring arm 50 40 and of shifting the speed changing means is done by a motor-device. A motor-device 166 similar to that described with reference to Figs. 6, 7 and 8 may be used and the circuit in which it is included may be the same as that illustrated in Fig. 45 8. The motor-device 166 acts directly on the speed-changing means, instead of through the shaft 52 of the radius measuring part 50, as in Figs. 6, 7, and 8. The ratchet-wheel 166 is fixed on a shaft 100 on which is fixed a worm 102 which 50 meshes with the teeth 55 on the sleeve 44, which latter, as hereinbefore described, shifts the disk 42 of the variable diameter pulley 37. The radius measuring arm 50 is fixed on a shaft 106 and its displacement is effected by a cam 108 on the 55 sleeve 44, which cam acts on the radius measuring arm 50, as by means of an arm 110 on the same shaft 106 as the arm 50. The cam 108 would also perform the function of the pawl 64 and rack-segment 66 and these could be omitted. 60

The means by which the return movement of the radius measuring part 50 is stopped or prevented has advantages in the spooling or reeling of wire. The contacts of the radius measuring part with the wire are successive and momentary. A momentary contact of the displaceable radius measuring device 50 with the high spot of each successive layer of wire as it builds in the coil on the spool S is sufficient to displace it, and the means for stopping back movement of said 70 displaceable part, or of operating it and holding it in its operated position, (several embodiments of which are shown herein) holds the said displaceable part 50 out of contact with the wire between successive momentary contacts. By 75

such method of operation the wire during winding is not liable to scratching by the continuous contact of the displaceable part therewith, or to marking resulting from impacts on rebound, and the quality of the wire wound on the spool or reel is improved. The degree of movement of the parts is diminished and the fluctuations of the mechanism driving the spindle which carries the spool or reel are diminished, and a more positive and regular action obtained.

As heretofore stated the means for changing the speed of the spool spindle 18 generically may have any suitable form or embodiment. The form shown here, comprising one pulley of uniform diameter and another pulley of variable diameter is a type in which the change of speed is proportional to the change of radius of the coil on the spool S for successive layers of wire, and hence the change in speed of the spindle shaft 18 is proportional to the displacement of the displaceable part 50.

The radius measuring arm 50 in the form of embodiment shown in Figs. 1-5 inclusive is preferably provided with a roller 150 at the place where contact is made with the coil on the spool, to reduce friction, and the roller and arm 50 are preferably made of light material to reduce the inertia.

Operation

Referring to Figs. 1 to 5 inclusive and 9, the drawn wire passes off the final capstan 15, to the spool S on the spindle 18 of the spooling mechanism 12. Between the final capstan 15 and the spool there is preferably provided a device 210 which controls the tension under which the wire winds onto the spool S. The tension device 210 can have any form, being here shown as an arm carrying a roller which is pressed against a loop in the wire by a spring. In proximity to the spool there is also provided a traversing device 115, which may have the construction of any of the devices of this character ordinarily used in spooling apparatus.

The spool spindle S is rotated from the shaft 20 (which is driven from the wire drawing mechanism through the sprocket wheel 35), through a variable transmission 30 comprising the pulley 33, belt 39, variable diameter pulley 37 and the shaft of the spindle 18. The discs 41, 42 of the pulley 37, at the beginning of the winding operation, are wide apart to provide a bearing surface of a relatively small diameter for the belt 39. At this time the speed relation is such that the spindle 18 is turned at a speed which provides a peripheral speed at the barrel of the spool S which is slightly less than the peripheral speed of the final capstan 15. The spool S having been previously placed on the spindle 18, the radius measuring arm 50 is placed in contact with the barrel of the spool S. The mechanism is then started, and the wire proceeds to wind in layers on the spool S, and build thereon a coil of wire of increasing diameter, and radius.

As the radius of the coil increases by reason of the building of successive layers, the measuring arm 50 is moved (Figs. 1-5) or displaced step by step from or in relation to the axis of the spindle 18. The movement of the measuring arm 50 is imparted to a segmental rack 54 through the shaft 52. The segmental rack 54 engages the pinion on the sleeve 44 and rotates the sleeve. The rotation of the sleeve, by reason of the thread engagement of the sleeve with the part 45, produces a movement of the sleeve

44 longitudinally of the shaft 18, and thereby moves the disc 42 of the variable diameter pulley 37 toward the disc 41, thus increasing the effective diameter of the pulley, 37 and decreasing the speed of rotation of the spindle shaft 18, and thereby decreasing the speed of rotation of the spool S to an extent that the peripheral speed of the surface layer of the wire on the spool is maintained substantially constant. The peripheral speed of the coil on the spool S, as the layers 10 build thereon is held substantially constant by the action of the radius measuring arm 50 and the actuating parts connected thereto, as just described, the peripheral speed of the coil throughout the building of the layers of wire 15 thereon, remaining always slightly less than the peripheral speed of the final capstan 15. Such a relation of peripheral speeds is important in the winding of fine sizes of wire. In winding wire of the size which has considerable tensile 20 strength, the coil on the spool S can be run at a peripheral speed equal to that of the final capstan 15, particularly if the tensile strength of the wire is sufficient to retard the driving force, or to produce a slip in the driving connections. 25 Fine wire would break under similar conditions.

When a spool S is filled, the radius measuring arm may be swung to one side, the spool S removed from the spindle and replaced by an empty spool.

Spools are not usually exactly cylindrical. The face of the barrel may not be perfectly cylindrical, or the bore of the spool may not be exactly co-axial with the face of the barrel. When the spool S is rotated, therefore, it has a greater 35 or less wobble. To prevent the eccentricities of the spool S, and therefore of the coil building on the spool, from vibrating the radius measuring arm 50, and thereby pulsating or fluctuating the rotation of the spool spindle 18, back movement 40 of the radius measuring arm 50 is prevented after each succeeding contact of the radius measuring arm 50 with the high point of an eccentric coil. The high point of an eccentric coil is designated by the letter x Fig. 4. As the radius measuring 45 arm 50 is displaced by contact with the eccentric portions of the coil, the pawl 64 on the arm 60 which projects from the sleeve 62 drops behind a tooth on the segmental rack 66. By making the pawl 64 in several parts 64^a, 64^b, 64^c of different 50 length, as shown in Fig. 4, the back movement of the arm 60 and therefore of the radius measuring arm 50 can be limited to a fraction of the length of a tooth.

Referring to Figs. 6, 7 and 8, wherein the work 55 of displaying the radius measuring arm 50 and of shifting the change-speed device 30 is done by a motor device 160, when a layer of wire builds on the coil, the finger 75 is moved to an extent to open an electric circuit, (the diagram of which has already been described), at 78. Thereupon the solenoid of the motor device 160 is energized and causes the armature to pull on the arm 67 to rotate the shaft 162^a, and the rotation of the 65 shaft 162^a through the action of the threads 68, thrusts the shaft toward the ratchet wheel 166 and causes the pawl 162 to turn the ratchet wheel and thereby move or displace the radius measuring arm 50 from the coil on the spool. Back 70 movement of the ratchet wheel 166 and of the arm 50 is prevented by the stop pawl 70. As the arm 67 on the shaft 162^a is pulled down by the armature, it strikes a make and break device 90 and opens an electric circuit which restores the 75

parts of the motor device 160 to their initial position, and at which position they are in readiness to impart another stepwise movement to the ratchet wheel 166 and arm 50 when the finger 75 again opens the make and break device 78. The movement of the ratchet wheel 166 also rotates the shaft 52, which shaft 52 acts on the variable transmission 30 in the manner hereinbefore described.

10 Referring to Figs. 10 and 11 the work of shifting the radius measuring arm 50 and the variable transmission 30 is done by a motor device 160 similar to that described in reference to Figures 6, 7 and 8. A finger 75 on the radius measuring arm 50 opens an electric circuit and energizes the solenoid of the motor device 160 when a layer of wire builds on the spool S, or an eccentric portion of the coil, through contact when the said finger 75, moves it to an extent to open 15 the circuit at 78. The motor device 160, in the manner already described, moves the ratchet wheel 166 stepwise, and the stepwise movement of the ratchet wheel 166 is imparted to the variable transmission 30 through the shaft 100, worm 102 20 and the teeth 55 on the sleeve 44, rotating the said sleeve. The rotation of the sleeve 44 is converted by the threads 45 to movement longitudinally of the spindle shaft 18, and thereby moves the disc 42 of the variable diameter pulley 37 25 toward the disc 41, thereby increasing the effective diameter of the pulley 37, and decreasing the speed of rotation of the spindle shaft 18. The radius measuring arm is retracted through and held by the action of the cam 108 against an arm 31 30 on a shaft 106 on which the radius measuring arm 50 is mounted.

The invention may receive other embodiments than those herein specifically illustrated and described.

35 What is claimed is:

1. A spooling or reeling mechanism for wire drawing machines or the like, comprising a spool or reel spindle, means for driving said spindle to rotate the spool or reel, and means for progressively diminishing the speed of rotation of said spindle as the radius of the coil of wire on the spool or reel increases with successive layers, said latter means comprising a part displaceable with relation to the axis of said spindle, a make and 40 break device on said displaceable part having a finger arranged to contact with the coil of wire on the spool or reel, and means controlled by said make and break device for displacing said displaceable part, by a small amount, from the axis of said spindle, following successive contacts of said finger with the coil on said spool, and at the same time control the action of said speed diminishing means.

2. A spooling or reeling mechanism for wire 45 drawing machines or the like, comprising a spool or reel spindle, means for driving said spindle to rotate a spool or reel thereon, means for changing the speed of said driving means, and means arranged to contact with the wire coiling on the 50 spool for acting on said speed changing means in accordance with the change in radius of a coil of wire on the spool or reel by reason of the change in the layers of wire thereon, said speed changing means being of a type in which the changes of speed are proportional to the change of radius of said coil for successive layers of wire, said speed changing means comprising a belt and a pair of pulleys, one of the pair of pulleys being of variable diameter and being acted on to effect 55 a change of its diameter directly proportional to

a lineal increase in radius of said coil and thereby change the speed of the driving means.

3. A spooling or reeling mechanism for wire 5 drawing machines or the like, comprising a spool or reel spindle, means for driving said spindle to rotate a spool or reel thereon, means for changing the speed of said driving means, and means for controlling the action of said speed changing means so as to diminish the speed of rotation of the spindle as the radius of a coil of wire on the 10 spool or reel increases with successive layers, comprising a part displaceable with relation to the axis of said spindle and arranged to contact with the coil of wire on the spool or reel and through such contact control the action of said 15 speed changing means, and means for retracting and holding said displaceable part clear of the wire between successive momentary contacts of said displaceable part with the wire of successive 20 layers.

4. A spooling or reeling mechanism for wire 25 drawing machines or the like, comprising a spool or reel spindle, means for driving said spindle to rotate the spool or reel, and means for progressively diminishing the speed of rotation of 30 said spindle as the radius of the coil of wire on the spool or reel increases with successive layers, said latter means comprising a part successively displaced from the axis of said spindle by small increments through contacts with the high portion 35 of successive layers of wire as they are wound on the coil and means for stopping return movement of said displaceable part following successive increments of displacement in such manner that said displaceable part is intermittently 40 and momentarily in contact with the wire of the coil and held so it cannot follow irregularities of the coil with respect to the axis around which it turns, and means cooperating with said displaceable part constructed and arranged to diminish the speed of rotation of said spindle coincident with said displacements.

5. A spooling or reeling mechanism for wire 45 drawing machines or the like, comprising a spool or reel spindle, means for driving said spindle to rotate the spool or reel, and means for progressively diminishing the speed of rotation of said spindle as the radius of the coil of wire on the spool or reel increases with successive layers, said latter means comprising a part successively 50 displaced from the axis of said spindle by small increments through contacts with the high portion of successive layers of wire as they are wound on the coil, a pawl and ratchet for stopping return movement of said displaceable part following successive increments of displacement in such manner that said displaceable part cannot move toward the axis of the coil to follow irregularities of the coil with respect to the axis around 55 which it turns, and means cooperating with said displaceable part constructed and arranged to diminish the speed of rotation of said spindle coincident with said displacements.

6. A spooling or reeling mechanism for wire 60 drawing machines or the like, comprising a spool or reel spindle, means for driving said spindle to rotate the spool or reel, and means for progressively diminishing the speed of rotation of said spindle as the radius of the coil of wire on the spool or reel increases with successive layers, said 65 latter means comprising a pivoted arm having a part thereon in proximity to the coil on the spool and which is successively contacted by the coil as the high portion of successive layers wind thereon and by such contacts moved out of contact 70 75

with the coil and from the axis of the spindle by small increments, and means for stopping return movement of said arm following successive increments of displacement in such manner that 5 said arm is intermittently and momentarily in contact with the wire and held so it cannot follow irregularities of the coil with respect to the axis around which it turns, and means cooperating with said displaceable part constructed and 10 arranged to diminish the speed of rotation of said spindle coincident with said displacements.

7. A spooling or reeling mechanism for wire drawing machines or the like, comprising a spool or reel spindle, means for driving said spindle to 15 rotate the spool or reel, and means for progressively diminishing the speed of rotation of said spindle as the radius of the coil of wire on the spool or reel increases with successive layers, said latter means comprising a part displaceable with 20 relation to the axis of said spindle, a contactor thereon in proximity to the coil of wire on the spool or reel arranged to contact intermittently therewith as the radius increases with successive layers of wire, and means acting to move said dis- 25 placeable part, by small amounts, from the axis of said spindle, following successive intermittent contacts of said contactor with the coil on the spool, and means cooperating with said displaceable part constructed and arranged to diminish 30 the speed of rotation of said spindle coincident with said displacements.

8. A spooling or reeling mechanism for wire drawing machines or the like, comprising a spool or reel spindle, means for driving said spindle to 35 rotate the spool or reel, and means for progressively diminishing the speed of rotation of said spindle as the radius of the coil of wire on the spool or reel increases with successive layers, said latter means comprising a part displaceable with 40 relation to the axis of said spindle, a contactor thereon in proximity to the coil of wire on the spool or reel arranged to contact intermittently therewith as the radius increases with successive layers of wire, and means acting to move said dis- 45 placeable part, by small amounts, from the axis of said spindle, and to stop return movement thereof, following successive contacts of said intermittent contactor with the coil on the spool, and means cooperating with said displaceable 50 part constructed and arranged to diminish the speed of rotation of said spindle coincident with said displacements.

9. A spooling or reeling mechanism for wire drawing machines or the like, comprising a spool or reel spindle, means for driving said spindle to 55 rotate the spool or reel, and means for progressively diminishing the speed of rotation of said spindle as the radius of the coil of wire on the spool or reel increases with successive layers, said latter means comprising a part displaceable with 60 relation to the axis of said spindle, electrical means for operating said speed diminishing means and a contactor associated with said displaceable part arranged to contact intermittently with the 65 high spot on successive layers of wire as they build the coil of wire on the spool, and to control the operation of said electrical means.

10. A spooling or reeling mechanism for wire drawing machines or the like, comprising a spool or reel spindle, means for driving said spindle to rotate the spool or reel, and means for progressively diminishing the speed of rotation of 5 said spindle as the radius of the coil of wire on the spool or reel increases with successive layers, said latter means comprising a speed-changing device, a displaceable contactor adjacent said spindle arranged to contact with a coil building 10 on said spindle, motor-means for doing the work of shifting said speed-changing device, and means under the control of said displaceable contactor for controlling the action of said motor-means.

11. A spooling or reeling mechanism for wire 15 drawing machines or the like, comprising a spool or reel spindle, means for driving said spindle to rotate the spool or reel, and means for progressively diminishing the speed of rotation of said spindle as the radius of the coil of wire on the 20 spool or reel increases with successive layers, said latter means comprising a speed-changing device, a displaceable contactor adjacent said spindle, motor-means for doing the work of moving said speed-changing device and said displaceable 25 contactor, and means under the control of said displaceable contactor for controlling the action of said motor-means, said contactor operating to effect a momentary action of said motor-means when a contact is made with any part of the coil 30 of wire building on the spool or reel, and the consequent action of said motor-means acting to displace said contactor to break contact with the coil and produce an increment of change in said speed-changing means.

12. Apparatus according to claim 11, further comprising a cam arranged to be turned by said motor-means and to act to displace said displaceable contactor, and having a contour which determines the degree of displacement of said contactor.

13. A spooling or reeling mechanism for wire drawing machines or the like, comprising a spool or reel spindle, means for driving said spindle to rotate the spool or reel, and means for progressively diminishing the speed of rotation of said spindle as the radius of the coil of wire on the spool or reel increases with successive layers, said latter means comprising a speed-changing device, a displaceable part adjacent said spindle, an electric motor and an electric circuit therefor, said electric motor being arranged to do the work of moving said speed changing device and said displaceable part, and a contactor on said displaceable part and electrical means controlled by said contactor for opening and closing the circuit to said electric motor, said contactor operating to effect a momentary admission of current to said electric motor when a contact is made with any part of the coil of wire building on the spool or 45 reel, and the consequent energization of said motor acting to displace said displaceable part and the contactor thereon to break contact with the coil and produce an increment of change in said speed-changing means.

HERMAN ZARAFU.
